SHELVING STRUCTURE

Application filed February 19, 1930. Serial No. 429,538.

An important object of the present invention is to provide a shelving structure of generally improved design.

Another object of the invention is to provide, in a shelving structure, improved means for supporting the shelves and rendering them vertically adjustable.

Another object of the invention is to provide in a shelving structure, improved means to render the shelves vertically adjustable quickly and easily and without the use of tools.

Another object of the invention is to provide an improved mounting for a bin front or panel used to partly close the space between the front edges of a pair of adjacent shelves.

Other objects of the invention will appear hereinafter.

20 In the drawings:

Fig. 1 is a front view of my improved shelving structure partly in section;

Fig. 2 a horizontal section taken on the line 2—2 of Fig. 1;

Fig. 3 a vertical section taken on the line 3—3 of Fig. 1 upon a larger scale;

Fig. 4 a horizontal section upon a larger scale taken on the line 4—4 of Fig. 3;

Fig. 5 a plan view partly in section of one 30 of the shelf corners;

Fig. 6 a sectional perspective view of two of the shelf-supporting beams;

Fig. 7 a sectional perspective view showing a joint between a shelf and an upright;

Fig. 8 an end view of the upper and lower parts of the shelving structure;

Fig. 9 a perspective view of one end of the bin front;

Fig. 10 a horizontal section taken through the bin front; and

Fig. 11 a vertical section taken through the panel for closing the space between the lower-most shelf and the floor.

The shelving structure includes a plurality of hollow uprights 1. For a structure having a single tier of shelves four of these uprights are required and they are designed for supporting additional shelves at either side of said tier when required, as indicated by dotted lines in Fig. 1. Each tier is formed

of a stout sheet metal blank which is formed into a substantially rectangular tubular shape by a simple rolling process. The margins 2 of the blank are turned outwardly at the middle of one of the longer sides of the rectangle at a right angle to said side and from a flat rib or fin of material width extending the height of the upright. Along opposite sides of said fin the upright is formed with two vertical rows of equally spaced elongated slots 3 opening into the interior of the upright. The slots in both rows are of the same shape and size and are similarly spaced along substantially the entire length of the upright. Formed in the margins 2 are bolt apertures 4 arranged in a vertical row and spaced similarly to the slots 3. Preferably the margins 2 are spaced slightly apart so that a side cover panel may be mounted between them, as indicated by dotted lines in Fig. 4.

A plurality of shelves 5 are adjustably supported between the uprights. Each shelf is formed of a sheet metal blank which is folded along its front and rear edges to form an integral, double ply beam 6. The end margins of the shelf blank are turned downwardly to form flanges 7, and each of said flanges is crimped inwardly to form a rib 8 extending along the length thereof. This rib serves to strengthen the flange and also has another purpose which will appear hereinafter. At each corner the shelf is formed with a square cut notch 9 which adapts the shelf to fit around the upright at each corner, dispose the beam 6 flush with the outer face of the upright and dispose the flange 7 so that its end portion abuts the rib formed by the upright margins 2. The latter extend at right angles from the inner face 10 of the upright and form therewith two corners into each of which a corner portion of a shelf is adapted to fit.

Each shelf is supported along its ends by two rigid angle beams 11. Each beam is preferably formed by a stout sheet metal blank folded longitudinally to form an upright web 12 and a horizontal flange 13 upon which the shelf rests. At each end the web 12 is reduced in width, and is formed with a notch or slot 14 extending straight upward

from the lower edge of the web. This notch gives the beam end a hook-like form to releasably interlock in any one of the slots. Each end of flange 13 is cut away as at 15 5 to provide clearance for the upright and forms a tongue 16 which extends past the upright to a point near the adjacent edge of the shelf. Thereby the latter is firmly supported at the upright. Extending between 10 the beams 11 is a cross beam 17. This beam is T-shaped in cross section having a flat top 18 and a depending central web 19. At an intermediate point each beam 11 has its flange 13 slit and depressed to form a flat 15 countersunk seat 20 for the ends of the beam top 18, the slit providing clearance for the web 19. The beam rests upon said seats with its top surface flush with the upper surfaces of beams 11 and the shelf rests flat upon all three of said beams with its ends supported by beams 11 and its medial portion supported by beam 17.

In assembling the shelving structure the top and bottom shelves are preferably first 15 mounted in place to hold the uprights properly positioned to receive the intermediate shelves. Since the upper and lower shelves are to remain in fixed positions they are preferably bolted as indicated at 21. The bolts 20 are passed through apertures 22 and 23 formed in the shelf flanges 7 and the beams 11 respectively and through certain of the apertures 4 in the upright margins 2. Each shelf and each beam 11 is provided with bolt 25 apertures so that the shelves and beams will all be interchangeable. Preferably the uprights will also be connected by bracing means to give rigidity to the structure. The bracing means, however, forms no part of the 30 present invention and is omitted to simplify the showing. The shelves are all mounted in place in the same manner. Each end beam 11 is first mounted in place by interlocking its hook-like ends in slots 3 located at the proper 35 level. Crossbeam 17 is then seated upon beams 11 and the shelf is placed upon the assembled beams. When the shelf is in position its front and rear edge beams 6 are flush or substantially flush with the outer 40 faces of the uprights and its end flanges 7 cover the outer sides of beams 11 and extend into the corners formed by the uprights. Here they bear against the margins 2 and their ribs 8 bear against the depending webs 45 12 of the beams. These ribs are springy and inwardly bowed and preferably make a close wedge-like fit between a margin 2 and the opposed beam 11 within the corner of the upright. The ribbed flanges then serve as 50 spacer means to prevent play at the interlocking connections and also as holding means to frictionally hold the shelf in place upon the beams.

When it is required to adjust a shelf to a 55 different level it is first lifted from the beams

by application of slight upwardly directed force to overcome the said frictional engagement and free the ribbed flanges 7 from the beams 11. The beams 11 and 17 are then accessible so that the beam 17 may be lifted 70 from the beams 11 and the latter separately removed and interlocked in other slots 3 at the new level. Thereupon the crossbeam 17 is placed in position upon beams 11 and the shelf is replaced thereon. The slots 3 75 are made considerably longer than the depth of the beam ends to provide ample clearance for easy manipulation of the latter into and out of interlocking position.

By supporting the shelves as described 80 the mounting and the adjustment thereof to different levels are greatly facilitated and the shelves are more strongly supported than when mere bolts are employed for securing them to the uprights. Furthermore 85 the interlocking connections between the shelves and the uprights are located in concealed and unobstructing positions. The surfaces exposed to view and those exposed to contact with the shelf contents in the 90 handling and storage thereof are all smooth. The feature of design which provides for the extension of the front and rear edges of the shelves outward to positions flush with the outer faces of the uprights is also very advantageous. This enables two similar shelving units to be disposed back to back without a gap between corresponding shelves of the 95 two units.

In some cases it is required to provide a 100 bin front or retaining panel to partly close the space between the forward edges of two adjacent shelves. I have provided an improved bin front designed to cooperate with the slotted uprights just described and adapt 105 the bin front to be readily removed and adjusted vertically in accordance with the shelf adjustment. This bin front comprises an elongated, rectangular sheet metal panel 24 folded inwardly along its lower edge to form 110 a horizontal flange 25 to rest upon the shelf and rolled at its upper edge as at 26. A vertical angle iron 27 is mounted at each end of panel 24 and secured by spot welding or other suitable means. One flange of this 115 angle iron is adapted to bear against the inner side of the adjacent upright and is formed with two tongues 28. Each tongue extends outwardly from the rear edge of the flange and then forwardly and is formed with a shouldered hook-like end designed to pass 120 into one of the slots 3 of the upright and releasably interlock therein. The tongues are so located that when they are interlocked in the proper slots above a shelf they will support the bin front upright with its lower flange 25 in contact with the shelf. By merely lifting and tilting the bin front it 125 may be easily removed for vertical adjust- 130

ment or to facilitate the removal or insertion of the shelf contents.

It is also required in some cases to close the space between the lowermost shelf and the floor. For this purpose I have provided a panel 29 whose structure is in every way similar to that of the bin front except that the rolled upper edge of the latter is replaced by a horizontal flange 30 to contact with the under side of the depending shelf beam 6. This panel is attached to the uprights in the same manner as the bin front and is held locked thereto by contact with the shelf beam 6 which prevents it from lifting and releasing.

While I have shown and described a very desirable form of my invention I do not wish to be limited strictly to this disclosure but reserve the right to make such changes as will lie within the scope of the claims.

What I claim is:

1. A shelving structure comprising a shelf; a plurality of uprights arranged in pairs and each formed with walls therealong disposed at an angle to each other and forming a corner to receive a corner portion of the shelf, one of said upright corner walls being formed with a plurality of vertically spaced elongated slots; a plurality of beams each extending between a pair of said uprights and into said corners thereof to support a shelf along opposite edges thereof; and tongues carried by said beams extending straight out longitudinally from the ends thereof and formed to releasably interlock in said slots and support the beams and shelf for vertical adjustment along the uprights, the shelf being supported for removal from the beams to facilitate the adjustment of the latter.

2. A shelving structure comprising a shelf; a plurality of uprights arranged in pairs and each formed with walls therealong disposed at an angle to each other and forming a corner to receive a corner portion of the shelf, one of said upright corner walls being formed with a plurality of vertically spaced elongated slots opening into the interior of the upright; a plurality of beams each extending between a pair of said uprights and into said corner thereof to support a shelf along opposite edges thereof; tongues carried by said beams extending straight outward longitudinally from the ends of the beams and formed to releasably interlock in said slots and support the beams and shelf for vertical adjustment along the uprights, the shelf being supported for removal from the beams to facilitate the adjustment of the latter; and spacer means carried by the shelf and formed and disposed for wedging between the beams and the uprights, within said corners, to prevent play of said tongues in the slots and frictionally hold the shelf and beams in place.

3. A shelving structure comprising a shelf;

a plurality of uprights arranged in pairs and each formed with walls therealong disposed at an angle to each other and forming a corner to receive a corner portion of the shelf, one of said upright corner walls being formed with a plurality of vertically spaced elongated slots; a plurality of beams each extending between a pair of said uprights and into said corners thereof to support a shelf along opposite edges thereof; tongues carried by said beams to releasably interlock in said slots and support the beams and shelf for vertical adjustment along the uprights, the shelf being supported for removal from the beams to facilitate the adjustment of the latter; 75 downwardly extending flanges carried by the shelf and adapted to be interposed between the beams and the uprights within said corners of the latter; and spacing means carried by said flanges for engagement with the uprights within said corners to prevent play of said tongues in the slots and frictionally hold the shelf and beams in place.

4. In a shelving structure, a shelf; an upright formed with walls therealong disposed at an angle to each other and forming a corner to receive a corner portion of the shelf; one of said upright corner walls being formed with a plurality of vertically spaced elongated slots; a shelf-supporting beam; a tongue carried by said beam to releasably interlock in said slots to support the beam and shelf and render them vertically adjustable along the upright, the shelf being supported upon said beam for removal therefrom without disturbing the connection of the beam with the upright; a flange carried by the shelf to interpose between the beam and the upright within said corner of the latter; and spacing means carried by said flange for engagement with the upright within said corner to prevent play of the interlocked tongue and frictionally hold the beam and shelf in place.

5. A shelving structure comprising a plurality of spaced uprights arranged in pairs; a plurality of shelf-supporting beams each extending between a pair of said uprights for supporting said shelf; means to connect said beams to the uprights and provide for their vertical adjustment along the uprights; a countersunk seat formed upon each of said beams intermediate the ends thereof; a cross beam loosely supported at its ends upon said seats; and a shelf resting upon all of said beams and adapted to be lifted therefrom for the adjustment of the beams.

6. A shelving structure comprising a shelf; a plurality of spaced uprights arranged in pairs and each formed with walls therealong disposed at an angle to each other and forming a corner to receive corner portions of the shelf; one of said upright corner walls being formed with a plurality of vertically spaced slots; a plurality of shelf-sup-

porting beams each extending between a pair of said uprights; tongues carried by said beams to releasably interlock in said slots and support the beams for vertical adjustment; a countersunk seat formed upon each of said beams intermediate the ends thereof; and a cross beam loosely supported at its ends upon said seats; the shelf resting upon all of said beams and being free to be lifted from them for the adjustment of the beams.

7. A shelving structure comprising a shelf; a pair of spaced hollow front uprights each formed at its rear side with walls therealong disposed at an angle to each other and forming a corner to receive a corner portion of the shelf, one of said upright corner walls being formed with a vertical row of spaced apertures opening into the interior of the upright; a pair of beams to support said shelf along its opposite ends extending into said corners; tongues carried by said beams to releasably interlock in said apertures and support the beams for vertical adjustment; a bin front in the form of a panel extending between said uprights; and angular tongues carried by said panel at its opposite ends and formed and disposed to releasably interlock in said slots above the shelf and support the panel just above the forward edge of the shelf and adapt it to be vertically adjusted according to the adjustments of the shelf.

8. A shelving structure comprising a shelf; four corner uprights each formed with walls therealong disposed at an angle to each other and forming a corner to receive a corner of the shelf; beams extending along the shelf ends and supporting them and extending straight fore-and-aft into said corners of the adjacent uprights, the corner walls of the latter directly opposed to the beam ends being formed with keeper apertures; locking tongues carried by the beams and extending straight outward longitudinally from the ends thereof to enter and releasably interlock in said keeper apertures; and reinforcing means carried by the shelf extending along the front edge thereof and unattached to the uprights.

9. A shelving structure comprising a shelf; four corner uprights each formed with walls therealong disposed at an angle to each other and forming a corner to receive a corner of the shelf; beams extending along and beneath the shelf ends and detachably supporting them and extending straight fore-and-aft into said corners of the adjacent uprights, one wall of each corner being directly opposed to the adjacent beam end and formed with vertically spaced keeper apertures; locking tongues carried by the beams and extending straight outward from the ends thereof to enter and releasably interlock in selected ones of said apertures; depending flanges carried by the ends of the shelf to interpose between the beams and the

uprights in the corners of the latter; and resilient locking and spacing means carried by said flanges and insertable therewith between the outer sides of the beams and the uprights within said corners to prevent play and displacement of the beams, give rigidity to the structure and yieldably hold the shelf down upon the beams.

10. A shelving structure comprising a shelf; four corner uprights each formed with walls therealong disposed at an angle to each other and forming a corner to receive a corner of the shelf; beams extending along and beneath the shelf ends and detachably supporting them and extending straight fore-and-aft into said corners of the adjacent uprights, one wall of each corner being directly opposed to the adjacent beam end and formed with vertically spaced keeper apertures; locking tongues carried by the beams and extending straight outward from the ends thereof to enter and releasably interlock in selected ones of said apertures; depending flanges carried by the ends of the shelf to interpose between the beams and the uprights in the corners of the latter; resilient locking and spacing means carried by said flanges and insertable therewith between the beams and the uprights within said corners to prevent play and displacement of the beams, give rigidity to the structure and yieldably hold the shelf down upon the beams; and a reinforcing beam integrally formed upon the shelf along the front edge thereof.

11. A shelving structure comprising a shelf; four corner uprights each formed with walls therealong disposed at an angle to each other and forming a corner to receive a corner of the shelf; beams extending along the shelf ends and supporting them and extending straight fore-and-aft into said corners of the adjacent uprights, the corner walls of the latter directly opposed to the beam ends being formed with keeper apertures; and locking tongues carried by the beams and extending straight outward longitudinally from the ends thereof to enter and releasably interlock in said keeper apertures.

In testimony whereof I hereunto affix my signature.

EMANUEL MICALLY.
